TOOL FOR CUTTING THE LOOPS OF VELVET
AND LIKE PILE FABRICS

Paul Schlempfer, Ohligs, Germany

Application August 12, 1936, Serial No. 95,606
In Germany April 8, 1935

7 Claims. (Cl. 139—44)

In wires or tools for cutting velvet or like pile fabrics and having an interchangeable blade, it is known for the blade to be displaceably mounted in the wire head so as to enable the whole of the cutting edge to be utilized. For this purpose, the 5 blade is mounted in the tool head so as to be pivotal either about its forward or about its rear end. In these constructions however the blade has to be shifted by hand.

It is an object of the present invention to mount 10 the blade resiliently in the wire head, so that the blade is shifted when the cutting pressure becomes excessive and, in particular, when the cutting edge becomes blunt.

The invention lies in so providing the blade, 15 which is pivotally mounted in the wire head, that it is under spring pressure acting counter to the cutting pressure and in the position of rest applies itself against a stop, whilst during the cutting operation it is moved away from this stop 20 with increasing cutting pressure and is pressed upon the base of the recess in which it is located. This occurs particularly when the part of the cutting edge nearest to the head of the tool has become blunt, that is, when the pressure exerted by 25 the loops of the fabric on this part of the blade increases. This increased pressure forces the pivotally mounted blade downwards, so that the blade sinks against the action of the spring means and 30 a different part of the cutting edge comes into play.

Advantageously, in accordance with one feature of the present invention, the blade is mounted so that the head of the blade, which is prolonged beyond the pivot point, applies itself with 35 its upper longitudinal edge against a spring disposed in the wire head, whilst the lower edge of the knife head rests against a shoulder provided in the wire head for the purpose of preventing unintentional escape of the blade, which is pivotally about a pin or bolt provided in the wire head.

In order to avoid projecting edges, projections, 40 or the like as far as possible, according to a further feature of the invention, a lug or flange is bent out of the upper edge of the wire head, beneath which a U-shaped spring is disposed about a pin, one limb of said spring pressing inwardly 45 against the lug whilst the angularly bent end of the other limb of the spring is located in a slot provided in the wire head. By this construction of the wire head the additional advantage is achieved that the U-shaped spring cannot be lost.

In this construction therefore the spring is located 50 between the side walls of the wire head, which makes the latter relatively thick. The in-

vention includes various further features which provide for the wire head being of the same thickness as in the case of the ordinary kind of tool in which the blade is not under spring pressure.

In one modification of the invention a resilient 5 finger resting on one wall of the wire or rod and engaging over the head of the blade is provided in continuation of the stop supporting the blade head. By means of this finger, the blade head is constantly pressed against the said stop except when the cutting pressure increases, due to the 10 blade becoming blunt, in which event the blade head is raised from the stop against the spring action of the finger.

In a further modification of the invention a 15 spring is disposed in the space between the lower edge of the blade and the bottom of the recess, this spring pressing against the lower edge of the blade and the bottom of the recess respectively. In this case also the blade head is only 20 as thick as a tool of the ordinary kind, the space already existing being utilized for receiving the spring.

In order that the invention may be clearly 25 understood and readily carried into practice I have appended hereto one sheet of drawings illustrating the same, and to which reference will now be made.

Figure 1 is a side elevation of a construction of 30 velvet cutting wire according to the invention, with the blade depressed on to the bottom of its recess.

Figure 2 is a side elevation of the tool with the 35 blade ready for use, that is to say, not depressed.

Figure 3 shows the manner in which the blade is inserted.

Figure 4 is a section on line IV—IV, Fig. 1.

Figure 5 is a section on line V—V, Fig. 1.

Figure 6 is a side elevation of a modified construction of the tool, before the blade has been 40 swung into position.

Figure 7 shows the tool of Fig. 6 with the blade 45 in position.

Figure 8 is a section on line VIII—VIII, Fig. 7.

Figure 9 is a plan of the tool of Fig. 7.

Figure 10 shows a further modified construction of the tool, with the blade in position.

Figure 11 is a section on line XI—XI, Fig. 10.

Referring now to the drawing, the velvet cutting wire or tool 1 has a recess 2 in which the blade is located. In the normal position (Figs. 2, 7 and 10) the bottom 3 of the recess is a comparatively great distance away from the lower edge 4 of the blade. At its forward part the blade has a hole through which a pin 5 passes.

This pin 5 is secured in the head of the tool and acts as a bearing or pivot for the blade (Figs. 3 and 6). The head 6 of the blade has an upper longitudinal edge 7 and a lower edge 8. When the blade has been inserted the edge 8 lies in front of the shoulder 9 of the stop 11 provided in the tool head 10. Opposite this stop 11, which has an incline 12 merging gradually into the plane of the tool head, there is provided the 10 cheek or flanged part 13 (Figs. 1-5), which is folded over from the upper edge of the tool head leaving a space between it and the main plane of the tool. Beneath the flange 13 there is disposed a U-shaped spring 15, which is arranged 15 about a pin 16. One limb 17 of the spring bears constantly against the flange 13, whilst the end 19 of the other limb 20 is bent and fitted into a slot 21 provided in the tool head. This bent end 19 rests against the edge 7 of the blade head 20 when the blade has been inserted (Fig. 2).

If, starting from Fig. 2, the part A of the cutting edge becomes blunt, the pressure exerted by the fabric loops on this part of the blade increases. Consequently the blade is depressed and 25 assumes the position shown in Fig. 1, the blunt part of the cutting edge being then beneath the upper edge 22 of the tool. In this way a new and unused part B of the cutting edge is brought into the effective position.

30 In the constructions according to Figs. 6-11 the blade has a longitudinal slot through which passes the pin 5 that is adapted to the shape of the slot, being so formed as to effect a bayonet-like locking of the blade when the latter is inserted.

Instead of a spring being arranged as in the embodiment described above, in the construction according to Figs. 6-9 there is provided, in continuation of the stop 11, a resilient finger 15 40 which lies on the wall 10 of the tool but is not rigidly attached thereto. The forward end of this finger 15 engages over the edge 7 of the blade head 6 and bears against this edge 7. The finger is about as thick as a wall of the tool 45 head, so that the tool head altogether is not thicker than the head of an ordinary double-walled velvet cutting wire.

The blade head 6 is provided with a V-shaped notch 23, and a corresponding recess 24 is arranged in the head of the tool. When the blade-head 6 is in the position shown in Fig. 7, the notch 23 registers with recess 24 but is longer than the latter. Thus a pointed instrument can be introduced into the recess and levered to lift the 55 blade over the stop 11. The recess 24 and notch 23 permit a ready insertion of the blade in the tool and a sure and accurate engagement of the head of the blade.

In the embodiment according to Figs. 10 and 60 11 the spring 15 is located in the space between the bottom 3 of the blade recess and the lower edge 4 of the blade. One limb 19 of the spring bears against the blade edge 4 and its other limb 17 bears against the recess bottom 3. As 65 shown in Fig. 11, the spring is no wider than the recess itself, so that the tool remains quite normal as regards its dimensions. Naturally, instead of this U-shaped spring a leaf spring may be employed. Furthermore, especially in the case of very thin tools with narrow recesses, an additional lateral recess may be provided for receiving the spring.

I declare that what I claim is:

1. A tool for cutting the loops of velvet and like pile fabrics, comprising a recessed holder, a blade disposed in said recess and pivoted at the head of the holder, a spring adapted to urge said blade in a direction opposite to that of the cutting pressure, and a stop against which said blade is adapted to rest in the normal position, said blade being adapted to be moved from said stop and depressed towards the bottom of said 10 recess when the cutting pressure increases.

2. A tool for cutting the loops of velvet and like pile fabrics comprising a recessed portion, a pivotally mounted blade disposed in said recess, a shoulder on said blade, a spring adapted to bear 15 on one edge of said shoulder in a direction opposite to that of the cutting pressure, and a lateral projection adapted to act as a stop for the lower edge of said shoulder, said blade being adapted to be moved away from said stop and 20 depressed towards the bottom of said recess when the cutting pressure increases.

3. A tool for cutting the loops of velvet and like pile fabrics, comprising a recessed portion, 25 a blade disposed in said recess and pivotally mounted on the head of the tool, a spring adapted to bear on the upper edge of said blade on the side of the pivot opposite the cutting portion of the blade, and a lateral projection at the head of said tool adapted to act as a stop for said 30 blade.

4. A tool for cutting the loops of velvet and like pile fabrics, comprising a cutting blade pivoted on the head of said tool and prolonged 35 on the side of the pivot opposite the cutting portion of the blade, a U-shaped spring adapted to bear on the upper edge of the prolonged portion of said blade, and a lateral projection at the head of said tool adapted to act as a stop for the lower edge of said prolonged portion. 40

5. A tool according to claim 4, wherein said spring is carried on the head of the tool and is housed in a recess formed by bending over the upper edge of the tool head, one end of the spring being bent over and engaging in a hole in 45 the tool head.

6. A tool for cutting the loops of velvet and like pile fabrics, comprising a cutting blade pivoted on the head of said tool and prolonged 50 on the side of the pivot opposite the cutting portion of the blade, a lateral projection adapted to act as a stop for the lower edge of said prolonged blade portion, and a resilient finger member forming a continuation of said projection and adapted to bear on the upper edge of said prolonged blade portion. 55

7. A tool for cutting the loops of velvet and like pile fabrics, comprising a blade disposed in a recessed portion of said tool and pivoted at the head of the tool, said blade being prolonged on 60 the side of the pivot opposite the cutting edge of the blade, a lateral projection adapted to act as a stop for the under side of said prolonged blade portion, and a spring disposed beneath the blade in said recessed portion of the tool on the 65 side of the pivot opposite said prolonged portion, said spring being adapted to urge the blade in a direction opposite to that of the cutting pressure.
